(57) **CLAIM**

The ornamental design for a cover for power adaptor, as shown and described.

DESCRIPTION

FIG. 1 is a perspective view of a cover for power adaptor showing my new design with the handle extended;
FIG. 2 is a second perspective view thereof, with the handle retracted;
FIG. 3 is a third perspective view thereof;
FIG. 4 is a fourth perspective view thereof;
FIG. 5 is a bottom plan view thereof;
FIG. 6 is a front elevational view thereof;
FIG. 7 is a left side elevational view thereof;
FIG. 8 is a right side elevational view thereof;
FIG. 9 is a rear side elevational view thereof; and,
FIG. 10 is a top plan view thereof.
